UNITED STATES PATENT OFFICE.

EDWARD H. KITFIELD, OF SWAMPSCOTT, MASSACHUSETTS.

ELECTRICAL SYSTEM OF HEATING.

SPECIFICATION forming part of Letters Patent No. 748,749, dated January 5, 1904.

Application filed October 26, 1903. Serial No. 178,493. (No model.)

To all whom it may concern:

Be it known that I, EDWARD H. KITFIELD, a citizen of the United States, residing in Swampscott, in the county of Essex and State 5 of Massachusetts, have invented an Improvement in Electrical Systems of Heating, of which the following description, in connection with the accompanying drawings, is a specification, like characters on the drawings 10 representing like parts.

This invention relates to an electrical heating system applicable for general heating purposes, and particularly well adapted, among other uses, for heating buildings, 15 houses, railway-cars operating on electric-railway systems, and other structures and vehicles.

The invention has for its object to provide 20 an electrical heating system in which the supply of current to one or more electric heaters, which may be made in the form of coils and located in the car or other structure, is automatically governed by the temperature of the car or other structure, as will be 25 described.

In the present instance I have shown the 30 invention as applied to a system for heating an electric-railway car, and for this purpose I employ a circuit-controller which is operated by a thermostat located within the car to change the condition of the circuit when 35 the temperature of the car reaches a predetermined point and means for maintaining the circuit through the heaters when the said circuit is opened by or at the thermostat.

Another feature of the invention consists 40 in providing means for selecting different temperatures at which the current may be applied to and cut off from the electric heaters, as will be described.

These and other features of this invention will be pointed out in the claims at the end of this specification.

Figure 1 represents an outline of an electric-railway car provided with a heating system 45 embodying this invention; Fig. 2, a diagrammatic view of the system represented in Fig. 1; Figs. 3 and 4, diagrammatic views like Fig. 2 to enable the operation of the system 50 to be clearly comprehended, and Figs. 5 and 6 modifications to be referred to.

In the present instance I have chosen to illustrate my system in connection with an

electric-railway car (indicated by the dotted lines in Fig. 1); but it will be understood 55 that I do not desire to limit the invention in this respect, as the system forming the subject of this invention is applicable to buildings, houses, and other structures.

In accordance with this invention the rail-way-car *a*, which is provided with one or more electric heaters *b* of any suitable, desired, or required construction, contains within it a thermostat which responds to the changes in temperature of the car and is employed to open and close the circuit containing the electric heaters, the said circuit being provided with means for maintaining the circuit through the electric heaters while the thermostat is moving from what may be 70 termed its "closed" to its "opened" position, and vice versa.

In the present instance the thermostat, which may be of any suitable or desired construction, is represented as a coil provided 75 with an arm *c* and made of two metal strips having different rates of expansion and contraction and commonly known as a "thermostatic" strip. The thermostat *c* co-operates with one or more circuit-terminals, (shown in 80 Figs. 1 to 4 as five in number and marked *d e f g h*,) which are connected by conductors *i j k l m* with the terminals or contact members *n o p q r* of a multiple circuit-controller provided with a movable contact member or 85 arm *s*, which is connected by a conductor 10 with a switch-arm 24, co-operating with a terminal 25, which is included in circuit with the source of current, herein represented as a trolley-wire 12, from which the current is 90 conducted to the car by the trolley-pole 13 in the usual manner, the trolley-pole being connected by the wire 26 with the terminal 25.

The thermostat *c* is normally included in circuit with one or more of the electric heaters *b*. In the present instance the heaters *b* are arranged in series, having one end connected with the ground 15 and their other end connected by wire 16 to one end of the coil of an electromagnet or solenoid 17, the 100 other end of which coil is joined by wire 18 with the thermostat *c*. The electromagnet or solenoid 17 is designed to maintain the circuit of the heating-coils *b* when the circuit is open at the thermostat *c*, and for this purpose the said solenoid governs the operation 105

of a circuit-controller comprising, as herein shown, a movable member 20, which is attached to the core 21 of said solenoid and cooperates with a stationary member 22, preferably located within the solenoid 17, so as to be within the magnetic field of said solenoid, for a purpose as will be described. The contact member or terminal 22 is joined by wire 23 to the switch-arm 24.

10 The terminals *d e f g h* of the thermostatic switch or circuit-controller are joined by wires 30 31 32 33 34 to the terminals or contact members 35 36 37 38 39 of a multiple switch or circuit-controller provided with a movable 15 contact arm or member 40, which is joined by the conductor 41 to the conductor 16, so that under conditions as will be described the coil of the solenoid may be shunted by the thermostat *c*. The core 21 of the solenoid 17 is 20 connected with the conductor 18 by a wire 42, which forms part of the shunt-circuit for the solenoid, as will be described. The operation of the heating system as thus far described may be readily understood by reference to Figs. 1, 2, 3, and 4.

25 As represented in Figs. 1 and 2, the heating system is in what may be termed its "normal" condition, in which the current is cut off from the heating-coils and from the solenoid, 30 the switch 24 being open, the switch-arm *s* being in contact with the terminal *n*, the switch-arm 40 being in contact with the terminal 39, and the thermostat *c* being in contact with the terminal *d*, which position of the thermostat may be considered as its starting position.

35 To enable the invention to be clearly understood, let it be supposed that the terminals *d e f g h* represent, respectively, 20°, 30°, 40°, 60°, and 70° of temperature. In this case the diagram Fig. 2 represents the temperature of the car as 20°. By reference to Fig. 2 it will be observed that the circuit of the heaters and solenoid is open at the switch 45 24. To heat the car, the operator throws the switch 24 into engagement with the terminal 25 and completes the circuit through the heaters *b*, which circuit is indicated in Fig. 2 by the full-line arrows and may be traced as 50 follows: from the trolley-wire 12 by the trolley-pole 13 and wire 26 to the switch 24, thence by wire 10, switch-arm *s*, terminal *n*, and wire *i* to the terminal *d*, with which the thermostat *c* is in engagement, thence by the thermostat *c*, wire 18, solenoid 17, wire 16, and heaters *b* to the ground 55 15. The solenoid 17 is thus energized and moves its core 21, so as to bring the circuit-terminal 20 into engagement with the terminal 22 and complete 60 a shunt-circuit for the thermostat *c*, thereby maintaining the heaters *b* in circuit after the thermostat under the influence of heat leaves the terminal *d* and moves toward the terminal representing the maximum degree of heat 65 to which it is desired the car should be heated, which maximum degree may be 70° and is represented by the terminal *h*. The shunt-

70 circuit is indicated by dotted arrows in Fig. 3 and may be traced as follows: from the trolley-wire 12 by pole 13 and wire 26 to switch 24, thence by wire 23, terminals 22 20, wire 42, wire 18, solenoid 17, wire 16, and heaters *b* to ground 15. By reference to Fig. 3 it will be observed that the circuit at the thermostat *c* is open and remains open until the said thermostat makes contact with the terminal *h*, representing 70°, at which time the temperature of the car has reached 70°. When the thermostat *c* engages the terminal *h*, as indicated by dotted lines, Fig. 3, a shunt-circuit 80 around the solenoid 17 is established, which may be traced as follows: from the trolley-wire 12 by pole 13 and wire 26 to switch 24, wire 23, terminals 22 20, wires 42 18, thermostat *c*, terminal *h*, wires *m* 34, terminal 39, switch 40, wires 41 16, and heaters *b* to ground 85 15. As soon as the shunt-circuit around the solenoid is established as described the core 21 drops and separates the terminals 20 22, thereby opening the circuit through the heating-coils and preventing the temperature exceeding 70°, which may be regarded as 90 the maximum. The current remains cut off from the heaters *b* until a circuit through the said heaters is again established, which 95 may be when the thermostat has contracted sufficiently to make contact with the terminal *d*; but I prefer to provide for reestablishing the circuit at different degrees between the maximum (represented as 70°) and the minimum, (represented as 20°.) To this end the intermediate terminals of the thermostatic circuit-controller—namely, *e*, *f*, and *g*—are provided, which may represent 100 temperatures of 30°, 40°, and 60°, respectively. 105 In practice it may be desired not to have the temperature of the car while in service drop below 60°, and in this case the operator places the switch *s* in engagement with the terminal *q*, as represented in Fig. 4, so that as the car 110 cools off and the thermostat *c* contracts and moves off of the terminal *h* and onto the terminal *g*, as represented by dotted lines in Fig. 4, the circuit through the heaters is again established, which circuit may be traced as 115 follows: from the trolley-wire 12 by pole 13 and wire 26 to switch 24, thence by wire 10 to switch *s*, thence by terminal *q*, wire *l*, terminal *g*, thermostat *c*, wire 18, solenoid 17, wire 16, and heaters *b* to ground 15. The solenoid 120 is again energized and attracts its core 21, thereby closing the shunt-circuit for the thermostat *c* between the terminals 20 22, which circuit may be traced as follows: from the trolley-wire by pole 13 and wire 26 to switch 24, thence by wire 23, terminals 22 20, wires 42 18, solenoid 17, wire 16, and heaters *b* to ground 125 15. The shunt-circuit around the thermostat and through the heaters *b* is maintained until the temperature of the car again reaches 70°, at which time the shunt-circuit around the solenoid is established, which circuit may be traced as follows: from the trolley-wire 12 by pole 13 and wire 26 to switch 130 15

24, thence by wire 23, terminals 22 20, wires 42 18, thermostat *c*, terminal *h*, wires *m* 34, terminal 39, switch 40, wires 41 16, and heaters *b* to ground 15. As soon as the shunt around the solenoid is established as described the solenoid 17 is deenergized and the core 21 drops, thereby opening the circuit of the heaters *b* between the terminals 20 22 until the car has cooled off sufficiently to again close the circuit of the heaters at the terminal *g* by the contraction of the thermostat *c*.

It will thus be seen that in the case just described 60° becomes the minimum and 70° the maximum, between which points the temperature is maintained by the movement of the thermostat from the terminal *g* to the terminal *h*, and vice versa.

Any two terminals of the thermostatic switch may be coupled together as the maximum and minimum by means of the multiple switches 40 *s*, which switches may be designated the "maximum" and "minimum" selective switches, the switch *s* being moved onto the terminal selected as the minimum and the switch 40 being moved onto the terminal selected as the maximum. This arrangement enables the heating system to be operated with a minimum current and at a great saving, for in the case of electric cars they may be heated to a comparatively low temperature while standing in the car-barn, which may be for hours, and yet be heated sufficiently to enable them to be heated to the maximum heat in a substantially short time—as, for instance, when they are put into service. To illustrate, while the car is not in use the switch *s* may be placed on the terminal *o*, representing 30°, and the switch 40 on the terminal 37, representing 40°, in which case the heaters *b* are automatically cut out of circuit when the temperature reaches 40° and are cut in circuit when the temperature falls to 30°.

While I may prefer to employ a thermostatic circuit-controller provided with a series of terminals corresponding to different temperatures and selective switches coöperating therewith, as above described, I do not desire to limit my invention in this respect, as the selective switches may be dispensed with and a thermostatic switch having a maximum terminal and a single minimum terminal may be employed, as represented in Figs. 5 and 6, wherein the thermostatic switch *c* is shown as normally in contact with the minimum terminal 50, connected by wire 10 with the switch 24, and as adapted to be expanded into contact with the maximum terminal 51, to which is connected the wire 41. The operation of the system shown in Figs. 5 and 6 is the same as that shown in Figs. 1 to 4, the solenoid 17 acting to shunt the thermostat *c* as soon as the current is turned on at the switch 24 and the thermostat acting to shunt out the solenoid when the maximum temperature is reached.

The circuit-terminals 20 22 are and may

be located in the magnetic field of the solenoid 17, so that any arc which might be formed between said terminals may be ruptured or blown out by said field.

I claim—

1. In an electrical system of heating, in combination, a heater, a circuit in which said heater is included, a thermostatic circuit-controller, a solenoid in circuit with said heater, and a circuit-controller operated by said solenoid, substantially as described. 75

2. In an electrical system of heating, in combination, a heater, a circuit in which said heater is included, a thermostat controlling said circuit, and an electromagnet in said circuit and controlling a shunt-circuit around said thermostat, substantially as described. 80

3. In an electrical system of heating, in combination, a heater, a circuit in which said heater is included, a thermostat controlling said circuit, and an electromagnet in said circuit and controlling a shunt-circuit around said thermostat, and a shunt-circuit for said electromagnet controlled by said thermostat, substantially as described. 85

4. In an electrical system of heating, in combination, a heater, a circuit in which said heater is included, a thermostat controlling said circuit, an electromagnet in said circuit and controlling a shunt-circuit around said thermostat, and temperature-selective switches governing the circuit of said heater, substantially as described. 90

5. In an electrical system of heating, in combination, a heater, a circuit in which said heater is included, a thermostat controlling said circuit, and means for maintaining the circuit of said heaters when said circuit is open at the said thermostat, substantially as described. 105

6. In an electrical system of heating, in combination, a heater, a circuit in which said heater is included, and a thermostat controlling said circuit to cut out said heater when the temperature reaches a predetermined point and to include said heater in circuit when the temperature falls to a predetermined point, substantially as described. 110

7. In an electrical system of heating, in combination, a heater, a circuit in which said heater is included, and a thermostat controlling said circuit to cut out said heater when the temperature reaches a predetermined point and to include said heater in circuit when the temperature falls to a predetermined point, and a translating device to maintain the circuit of the heater when the said circuit is opened by the thermostat, substantially as described. 115

In testimony whereof I have signed my name to this specification in the presence of two subscribing witnesses.

EDWARD H. KITFIELD.
